UNITED STATES PATENT OFFICE.

JOHN P. MAGUIRE, OF MARTINS FERRY, OHIO.

ELECTRIC HEATER FOR THE ROLLERS OF METAL-ROLLING MACHINES.

Application filed January 22, 1925. Serial No. 4,039.

To all whom it may concern:

Be it known that I, JOHN P. MAGUIRE, citizen of the United States, residing at Martins Ferry, in the county of Belmont and

5 State of Ohio, have invented certain new and useful Improvements in Electric Heaters for the Rollers of Metal-Rolling Machines, of which the following is a specification.

10 This invention relates to a highly novel means for heating the coacting oppositely rotating rollers of a metal rolling machine without interfering with the usual operation of the roller.

15 One of the important objects of the present invention is to provide an electric heater which is adapted to be used in conjunction with each of the rollers, means being associated with the heater for holding the same

20 in yieldable engagement with the respective rollers.

25 A further object is to provide a device of the above mentioned character, wherein the rollers may be heated uniformly, further more saving considerable time and labor in heating the rollers so that the same may properly function in their operation. The provision of an electric heater of the above mentioned character will furthermore prevent the roller becoming cracked as often results from the manner in which the rollers of a metal rolling machine are now generally heated.

30 A further object is to provide an electric heater of the above mentioned character, which may be easily and readily attached in position on the frame of a metal rolling machine of any well known construction without necessitating any material alteration of

35 the latter.

40 A still further object is to provide a device of the above mentioned character, which is simple in construction, inexpensive, and furthermore adapted for the purposes for

45 which the same is designed.

Other objects and advantages of this invention will become apparent during the course of the following description.

50 In the accompanying drawings forming part of this specification and in which like numerals designate like parts throughout the same:—

Figure 1 is a side elevation of the frame and the coacting rollers supported therein

of a metal rolling machine showing my invention associated therewith, and

Fig. 2 is a sectional view through the heater and a portion of one of the rollers.

In the drawing wherein for the purpose of illustration is shown the preferred embodiment of my invention, the numerals 1 and 2 designate the spaced vertical standards of the roller supporting frame of any conventional type of metal rolling machine, the coacting rollers which are mounted at their respective ends in the standards 1 and 2 being illustrated at 3 and 4 respectively.

The rollers are adapted for frictional engagement with each other and rotate in the opposite directions in the manner well known in the art. The lower roller 3 is mounted to be driven by the drive shaft 5 in the usual manner.

My improved electric heater comprises an elongated casing 6, the inner face of which is curved as illustrated at 7 to conform with the configuration of each of the rollers. Suitable anti-friction rollers 8 are associated with the curved face 7 of the casing 6 and engage the rotatable rollers in such a manner as to space the heater from the latter. An electric heating unit designated generally by the numeral 9 of any suitable construction is disposed within the casing 7 and is insulated therefrom by the insulation 10. The heating unit is adapted to extend for substantially the full length of the casing and is disposed adjacent the curved inner face 7 in a manner clearly illustrated in Fig. 2.

An electric heater is provided for each of the rotatable rollers, one of the heaters being disposed on one side of the frame for cooperation with the lower roller 3 while the other heater is disposed on the opposite side of the frame for cooperation with the upper roller 4. This is more clearly illustrated in Fig. 1.

A yieldable support is provided for each heater and to this end, there is provided a pair of coiled springs 11 and 12 respectively at each end of the casing of each heater. The inner ends of the cross springs are fastened to the ends of the casings while the opposite ends of the springs are detachably secured to the standard of the roller supporting frame.

In rolling mills, when steel bars are placed between the rollers, the top roller is forced

upwardly between the vertical standards of the roller supporting frame depending upon the thickness of the bar which is placed between the rollers and at a distance which 5 the lower end of the rotatable screws associated with the standards of the frame are located with respect to the ends of the upper rollers. At the same time, the top roller is forced rearwardly and when the bar passes 10 between the rollers, the top roller will drop down again and come in contact with the bottom roller and simultaneously rebound forward for a slight distance. Thus by yieldably supporting the electric heaters, 15 the various movements of the upper rollers will not effect the displacement of the electric heater and cause the same to be broken off as would occur if the electric heater was not supported by the springs 11 due to the 20 action of the rollers. Also the bottom roller will frequently cause the standards to spread apart and as rolling conditions change, the standards are drawn together or separated so that the provision of the coiled 25 springs for the supporting of the lower electric heater will permit the adjustment of the standards without affecting the bottom electric heater.

The arrangement of the electric heater on 30 the opposite sides of the frame enables the rotatable rollers 3 and 4 to be heated during the operation of the metal rolling machine and furthermore the rotatable rollers will be heated uniformly. After the proper degree 35 of heat has been reached, the current to the heating units in the heaters supplied by the wiring 13 may be cut off. The provision of a device of the above mentioned character, will save considerable time and labor as 40 well as expense and will at all times be positive and efficient in carrying out the purposes for which the same is designed.

While I have shown the preferred embodiment of my invention, it is to be understood 45 that various changes in the size, shape and arrangement of parts may be resorted to without departing from the spirit of the invention and the scope of the appended claims.

50 Having thus described my invention, what I claim as new is:—

1. In combination with a metal rolling machine including the coacting oppositely rotating rollers, and the supporting frame 55 therefor, of an electric heater for heating each of said rollers during the operation thereof, and means for yieldably supporting the heaters in engagement with the respective rollers.

60 2. In combination with a metal rolling

machine including the coacting oppositely rotating rollers, and the supporting frame therefor, of an electric heater for heating each of said rollers during the operation thereof, means for yieldably supporting the 65 heaters in engagement with the respective rollers, said means comprising a pair of coiled springs secured at one end to each end of the heater, the opposite ends of the coiled springs being secured to the adjacent portions of the frame. 70

3. In combination with a metal rolling machine including the coacting oppositely rotating rollers, and the usual supporting standards therefor, of an electric heater for 75 each of said rollers, the same comprising an elongated casing, the inner face thereof being curved, anti-friction rollers carried by the inner curved face of the casing and engaging the respective rollers, and a heating unit arranged in the casing adjacent the curved inner face thereof and insulated therefrom.

4. In combination with a metal rolling machine including the coacting oppositely 80 rotating rollers, and the usual supporting standards therefor, of an electric heater for each of said rollers, the same comprising an elongated casing, the inner face thereof being curved, anti-friction rollers carried by 85 the inner curved face of the casing and engaging the respective rollers, and a heating unit arranged in the casing adjacent the curved inner face thereof and insulated therefrom, and coiled springs secured at one end to the outer end of the casing, the opposite ends of said springs being secured to the adjacent standards. 90

5. In combination with a metal rolling machine including the coacting oppositely 100 rotating rollers, and the usual supporting standards therefor, of an elastic heater for each of said rollers, the same comprising an elongated casing, the inner face thereof being curved, anti-friction rollers carried by 105 the inner curved face of the casing and engaging the respective rollers, a heating unit arranged in the casing adjacent the curved inner face thereof and insulated therefrom, coiled springs secured at one end to the outer end of the casing, the opposite ends of said springs being secured to the adjacent standards, one of said heaters being disposed on one side of the frame for cooperation with one roller, another heater being disposed on the opposite side of the frame for cooperation with the coacting roller. 110 115

In testimony whereof I affix my signature.

JOHN P. MAGUIRE.
